UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR AN OVAL ARM FOR CHANDELIER AND BRACKETS.

49,389.

Specification for Design.

Patented July 18, 1916.

Application filed April 27, 1916. Serial No. 94,080. Term of patent 3½ years.

To all whom it may concern:

Be it known that I, CHARLES E. JONES, a citizen of the United States, residing at Chicago, in the county of Cook and State of Illinois, have invented a new, original, and ornamental Design for an Oval Arm for Chandeliers and Brackets, of which the following is a specification, reference being had to the accompanying drawing, forming part thereof.

Figure 1 is a side view of an oval arm for chandeliers and brackets, showing my new design. Fig. 2 is a sectional view of the same. Fig. 3 is a back view of the same.

I claim:

The ornamental design for an oval arm for chandeliers and brackets, as shown.

CHARLES E. JONES.
